SNAP FASTENER

Harold J. Reiter, Chicago, Ill.

Application January 14, 1936, Serial No. 59,001

10 Claims. (Cl. 24—224)

This invention relates to snap fasteners and is an improvement upon the fasteners disclosed in my copending applications for patents for Sliding fastener, filed April 30, 1935, Serial No. 19,005, and for Spring fastener, filed June 20, 1935, Serial No. 27,468. In application Serial No. 19,005, I have shown a fastener in which a stud is inserted axially through an enlarged part of an opening and then moved transversely in the opening to lock it in place. In application Serial No. 27,468, the locking means consists of spring fingers extending integrally from one of the socket parts, thereby eliminating the necessity for separate springs.

15 The present invention contemplates the provision of a socket comprising a shell member, an apertured plate member and a separate annular spring held therebetween, which spring, however, is cut from a sheet of material in the form 20 of a preferably complete ring with symmetrical cooperating fingers extending inwardly from the periphery of and partway across the annular ring.

25 The present invention further contemplates the provision of means on the spring for preventing it from rotating relatively to the remaining socket parts.

30 The present invention further contemplates the provision of means for making easy and inexpensive, the assembly of the cap with the socket.

35 The present invention further contemplates the provision of a socket held to one side of a sheet of material by a cap arranged on the other side of the sheet, which socket can be readily assembled and is well adapted for economical production in large quantities.

The various objects of this invention will be clear from the description which follows and from the drawing, in which,

40 Fig. 1 is a vertical section of my improved socket as it appears secured to a sheet of material and in cooperative locking engagement with a cooperating stud secured to another sheet.

45 Fig. 2 is a bottom plan view of the same, part of the socket plate being broken away to show the overlying structure.

Fig. 3 is a perspective view of the three socket parts which are assembled and secured to one side of a sheet of material to form the complete 50 socket.

55 In the practical embodiment of my invention which I have shown by way of example, the socket comprises three parts, namely, the plate member 10, the spring 11, and the shell or cup member 12. As shown in Fig. 3, the plate member 10 com-

prises a flat plate-like bottom portion provided with an opening 13. Said opening has an enlarged central part 14 adapted for the reception of the stud 15 which is suitably secured to the sheet 16, and is of larger diameter than that of the stud. Extending transversely from the enlarged part 14 of the opening is the elongated opening part 17, which is of substantially the diameter of the neck of the stud 15. Outstanding from the periphery of the plate portion of the 10 plate member 10 is the flange 18, said flange being bent about the lower peripheral portion of the cup or shell member 12 into the position shown in Fig. 1 when the parts are assembled.

The spring 11 is preferably cut in one piece 15 from a sheet of suitable material such as brass or the like, and comprises a circular annular part or ring 19 provided with a serrated outer edge 20 forming a series of teeth 21 in said edge. Projecting inwardly from the annular part 19 20 is a pair of cooperating spring fingers 22 and 23. Said fingers are symmetrically arranged about a diameter of the spring and at their bases 24, are integrally joined to the ring. Said fingers terminate a sufficient distance inwardly from the 25 points of the ring opposite the base 24 to provide a space wherein the stud 15 may be locked between the ends of the fingers and the inner circular edge 25 of the ring, after the stud is moved past the fingers.

30 Preferably, the teeth 21 are turned upwardly at an angle to the plane of the remainder of the ring as indicated in Fig. 1 so that said teeth may bite into the inner surface of the flange 18 and thus prevent rotation of the spring ring relatively 35 to the plate and maintain said fingers 22 and 23 in their correct positions relatively to the opening 13 of the plate. The ends 26 of said fingers are spaced apart a distance less than the diameter 40 of the neck of the stud 15 so that said neck may be forced therewith in either direction, the fingers 45 yielding when the stud is so moved transversely of the opening 13 and past said ends 26. As will be seen from Fig. 2, said ends 26 of the fingers 50 inwardly overhang the elongated part 17 of the opening 13.

To complete the socket, the cup or shell member 12 is provided. Said shell member is provided with a central domed portion 28 which terminates in a peripheral conical portion 29. 50 It will be seen that the flange 18 is bent into contact with said conical portion when the shell and the cup member are assembled with the spring therebetween, thereby holding the socket parts securely in place. At suitably spaced in- 55

5 tervals in the domed portion 28, are provided the outstanding projections 30 which enter the material 31, on one side of which the socket is attached. Said projections thereby prevent rotation of the socket relatively to the sheet 31 to which the socket is secured.

10 In order to secure the socket as a unit to the sheet 31, a central opening 32 is provided in the shell member 12 through which opening the attaching member of the socket cap (shown in the form of an eyelet) is passed and flanged. Said cap comprises the inner flanged eyelet member 33 having a central eyelet 34 therein adapted to be passed through the sheet 31 and through the 15 shell member opening 32 and to be flanged on the interior face of said shell member. To permit easy flanging of the eyelet to secure the parts together, a series of suitable short longitudinal slits as 35 extend a short distance from the end 20 of the eyelet whereby a suitable flanging tool may readily split the eyelet along the lines determined by the slits 35 and bend the thus split parts 36 on to the inner face of the shell member. The eyelet is preferably covered by a cap- 25 ping or covering member 37 bent about the periphery of the eyelet member 33 and concealing the member 33.

30 It will be noted that the shell member, plate and spring may be pre-assembled as a unit and sold in their assembled state and that the cap member may have its parts 33 and 37 pre-assembled and thus sold, so that the user may assemble the cap with the socket in a manner customary in the trade. To assemble the socket parts, the 35 spring 11 is dropped into the plate member 10 in such position that the fingers 22 and 23 are arranged at opposite edges of the opening 13 as shown in Fig. 2. The shell member 12 is then dropped into the plate member and into the 40 flange 18 thereof whereafter said flange is bent on to the conical portion 29 of the shell member, thus to secure the parts together and to cause the teeth 21 to bite into the flange 18 and to prevent rotation of the spring 11 under the stresses 45 of use. The thus assembled socket is arranged at the desired point of the sheet 31 whereafter the eyelet 34 of the cap is forced through the material and through the opening 32 and flanged, thereby securing the socket parts together in 50 the positions shown in Fig. 1.

55 The socket is used in operation by inserting the stud 15 axially to the enlarged part 14 of the opening 13, after which the stud is moved transversely into the elongated part 17 of the opening 55 and past the ends 26 of the fingers. The stud is thereby locked in the position shown in Fig. 2 and cannot be axially withdrawn from the socket. It can be withdrawn only first by a transverse movement to the enlarged part 14 of the opening, 60 after which the stud may drop out or may be moved out of the opening and the sheets 16 and 31 thus separated.

65 It will be seen that I have provided a fastener socket and securing means therefor adapted to be manufactured economically in large quantities and well designed to meet the severe requirements of practical use.

70 While I have shown and described a specific embodiment of my invention, I do not wish to be understood as limiting myself thereto but intend to claim my invention as broadly as may be permitted by the state of the prior art and the scope of the appended claims.

I claim:

75 1. In a fastener of the character described, a

one-piece plate member comprising a plate portion having a transversely elongated opening therein and a flange outstanding from the periphery of the plate portion, a shell member having a central domed portion and a peripheral 5 conical portion, the domed portion being provided with a central opening and with a series of spaced projections, and a one-piece spring of flat sheet material having a serrated outer edge held between said members and comprising a ring 10 portion and symmetrical spring fingers, each integral at one end with the ring portion and terminating in a free end in inward spaced relation to the ring, the free ends of said fingers inwardly overhanging said opening and being spaced apart 15 a sufficient distance to permit the passage of a cooperating stud forcibly therethrough in either direction, the flange of said plate member being bent about the conical portion of the shell member with the spring held therebetween. 20

2. In a fastener of the character described, a shell member, a plate member having an elongated opening therein and flanged about the periphery of the shell member, and a spring of a single piece of flat sheet material arranged on 25 the plate member and provided with a serrated periphery engaging one of said members and preventing rotation of said spring relatively to said members, said spring having integral fingers projecting inwardly from the periphery thereof 30 and inwardly overhanging the opening.

3. In a fastener of the character described, a plate member having an elongated opening terminating at both ends inwardly of the edge of the plate member, a shell member secured to 35 the plate member, and a spring resting on the shell member and maintained in place by the plate member, said spring comprising a single piece of sheet material having a closed annular ring portion and having a pair of similar spaced 40 apart fingers projecting inwardly from the ring portion and each integral at one end therewith and free at the other end and adapted to be forced apart transversely to lock a stud therebetween.

4. In a fastener of the character described, a 45 spring formed of a single piece of sheet material, said spring having a completely closed annular ring portion and having a pair of fingers each integral at one of the ends thereof with said ring portion and extending across the opening of and 50 from the inner edge of said ring portion and terminating in a free rounded end engageable directly by and yieldable under the pressure of the cooperating stud.

5. In a fastener of the character described, a 55 one-piece spring comprising an annular ring portion having peripheral teeth thereon, and a pair of spring fingers integral at their bases with said annular ring portion and extending partway 60 across said annular ring portion and provided with free ends spaced from each other and adapted to yield under the pressure of the cooperating stud.

6. A spring for a fastener of the character described, comprising an annular ring portion and 65 a pair of symmetrically arranged spaced apart similar fingers extending inwardly from the inner edge of said annular ring portion, and terminating in free rounded ends spaced from each other, and from the ring portion and adapted to yield 70 under the pressure of a cooperating stud, the space between said fingers being greatest at the center of said ring portion and least at the ends of the fingers.

7. A one-piece spring for a fastener of the char- 75

acter described comprising an uninterrupted annular ring portion having its outer peripheral edge portion bent out of the plane of the remainder of said ring portion, and a pair of stud-engaging fingers spaced apart throughout the lengths thereof and integral with and extending partway across said ring portion and terminating in free rounded ends.

5. A spring for a fastener of the character described, said spring being formed of a single piece of sheet material and comprising a ring portion having a serrated outer edge portion and a circular inner edge, said serrated portion being bent out of the plane of the remainder of said spring, and a pair of similar fingers integral with the ring portion and extending partway thereacross and adapted to yield under the transverse pressure of a cooperating stud.

9. In a fastener of the character described, a shell member having a domed portion provided with spaced projections and with an opening, a plate member having an elongated stud-receiving opening and flanged about the periphery of the shell member, a sheet metal spring having a ring portion, part of which is bent out of the plane of

the remainder thereof, said spring having fingers each integral at one end with the ring and extending partway thereacross, said spring resting on the plate member with the fingers thereof overhanging said opening, and a cap member having a preslotted eyelet, adapted to be arranged on one side of a sheet of material with the eyelet passing through the sheet and through the opening of the shell member and flanged on to said shell member, to secure the cap member to the sheet and to the sheet member.

10. In a socket fastener, a shell member provided with spaced projections, a plate member having an elongated stud-receiving opening therein, a peripheral flange on the plate member 15 bent about the periphery of the shell member, a one-piece spring on the plate member, said spring having a ring portion held in place by said members and having a pair of cooperating stud-engaging fingers extending partway across the ring portion and inwardly overhanging the elongated opening, and means adapted to be arranged on one side of a sheet of material for securing the shell member to the other side of the sheet.
